US0D1053464S

(12) **United States Design Patent** (10) **Patent No.:** **US D1,053,464 S**
(45) **Date of Patent:** **** Dec. 3, 2024**

(54) **PROTECTIVE LINER**

(71) Applicant: **Ningbo JieMai Safety and Protective Equipment Co., Ltd.**, Zhejiang (CN)

(72) Inventor: **Kang Qiu**, Zhejiang (CN)

(73) Assignee: **Ningbo JieMai Safety and Protective Equipment Co., Ltd.**, Ningbo (CN)

(**) Term: **15 Years**

(21) Appl. No.: **29/849,283**

(22) Filed: **Aug. 10, 2022**

(30) **Foreign Application Priority Data**

Jul. 26, 2022 (CN) 202230480693.4

(57) **CLAIM**

The ornamental design for a protective liner as shown and described.

DESCRIPTION

FIG. 1 is a top, front and right side perspective view of a protective liner showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the protective liner which form no part of the claimed design.

1 Claim, 8 Drawing Sheets
